UNITED STATES PATENT OFFICE.

MARY LOUISE MCCLURE, OF COSHOCOTON, OHIO.

SANITARY ATTACHMENT FOR WATER-CLOSET SEATS.

1,193,405.

Specification of Letters Patent. Patented Aug. 1, 1916.

Application filed May 13, 1916. Serial No. 97,345.

To all whom it may concern:

Be it known that I, MARY LOUISE MCCLURE, a citizen of the United States, residing at Coshocton, in the county of Coshocton, 5 ton and State of Ohio, have invented certain new and useful Improvements in Sanitary Attachments for Water-Closet Seats, of which the following is a specification.

This invention relates to sanitary attachments for closet seats and has for one of its objects to provide a simply constructed device including a supporting or base member, a plurality of superimposed relatively thin sheets of paper, preferably medicated 10 or sterilized, and detachably connected to the base member, and means for detachably coupling the base member and its complement of superimposed sheets upon the lower face of the cover member of a water closet 15 seat, in position for the sheets to be consecutively disposed upon the closet seat and torn off after using.

With this and other objects in view, the invention consists in certain novel features 20 of construction as hereinafter shown and described and then specifically pointed out in the claims; and in the drawings illustrative of the preferred embodiment of the invention Figure 1 is a side view, Fig. 2 is 25 a front view of a conventional water closet including the bowl, seat, and seat cover, with the improvements applied, Fig. 3 is an enlarged perspective detail of a portion of the device illustrating the construction more 30 fully, and Fig. 4 is an enlarged detached perspective view of one of the holding clips.

The improved device comprises a base or supporting member represented as a whole 35 at 10 and preferably of relatively heavy 40 and tough card board or the like and corresponding substantially in outline to but larger than the cover member of a water closet seat, the cover being represented conventionally at 11. The closet seat is represented conventionally at 12.

Bearing upon the base member 10 are a plurality of sheets of relatively thin material such as tissue paper or the like and represented at 13, and corresponding in outline 45 to the base member 10 and each with an opening corresponding substantially to but smaller than the opening of the seat 12. The base member 10 is formed with a downwardly directed projection 14 while each of 55 the sheets 13 is formed with a like projec-

tion 15, the projections being adapted to extend between the hinges 16 of the closet seat and its cover.

The margin of the opening in each of the sheets 13 is provided with a plurality of clefts 17 spaced at short intervals, so that the portion of the sheet which overhangs the opening of the seat 12 will readily bend inwardly over the edge of the opening in the seat when in use. Formed upon each of the sheets 13 is a guard portion 18 which hangs downwardly with the bowl of the closet when the sheet 13 is in operative position. The guard portions 18 are perforated to receive a holding cord or tape 19. The superimposed projections 14 and 15 are perforated to receive cords represented at 20 whereby the device may be tied to the hinges 16. At their upper portions and at intermediate points, the members 10 and 13 are 25 provided with clefts 21 and with registering apertures 22 to receive binding cords or tapes 23 by which the parts 10 and 13 are united.

Attached to the cover member 11 at suitable intervals are clip devices, one of which is shown detached in Fig. 4, and each comprising a flat plate 24 adapted to be secured to the cover 11 by screws or like fastening devices and each including a tongue 25 beneath which the cords or tapes 23 are disposed to detachably secure the base 10 and the superimposed sheets to the cover. By this means, the sheets are held only by the cords or tapes 23 and adapted to be detached one at a time and laid over the seat 20, the lower part of each sheet being held by the cords 20. After using, the sheet which has been turned down is torn off from the holding cords 20 and thrown into the 25 bowl, so that a fresh sheet may be turned down over the seat each time the closet is used. When the sheets are all used, they are renewed by detaching the cords 20 and applying the base 10 to a new set of the 30 sheets and the cords 23 engaged with the clips.

Having thus described my invention, what I claim and desire to secure by Letters Patent is:

1. A device of the class described including a base member having a projection, a plurality of sheets of relatively thin material superimposed upon said base and each having an opening and a projection corre- 110

sponding to the base member, means operating through the projections of the base and of the sheets and adapted to connect the same to the cover member of a water closet seat, binding cords uniting the base and the sheets, and a plurality of clip devices adapted to be connected to said cover and engaged by said cords.

2. A device of the class described comprising a base member, a plurality of sheets of relatively thin material superimposed upon the said base and each having an opening and a plurality of registering clefts in their margins and a plurality of registering apertures spaced from the clefts, binding cords extending through the clefts and

through the apertures, and means adapted to attach said cords to a closet seat cover.

3. A device of the character described comprising a base member, a plurality of sheets of relatively thin material superimposed upon the said base and each having an opening and a plurality of registering clefts in their margins and a plurality of registering apertures spaced from the clefts, binding cords extending through the clefts and through the apertures, and a plurality of clips adapted to be attached to a closet seat cover and engaged by said cords. 25

In testimony whereof I affix my signature. 30

MARY LOUISE McCLURE. [L.S.]
